VACUUM CLEANER

William B. Oaks, Detroit, Mich., assignor to
 Eureka Vacuum Cleaner Company, Detroit,
 Mich., a corporation of Michigan

Application March 25, 1940, Serial No. 325,876

7 Claims. (Cl. 15—8)

This invention relates generally to floor cleaners and refers more particularly to vacuum cleaners.

One type of vacuum cleaner which is used extensively for cleaning floor surfaces comprises a housing or casing having wheels supported on the surface of the floor to be cleaned and having a handle for propelling the casing over the floor surface. Located in the housing is a motor driven blower having the intake side communicating with a nozzle opening and having the exhaust side communicating with a dirt or dust receptacle usually carried by the handle. In accordance with conventional practice, the motor is supported in the housing with the axis of the drive shaft extending horizontally, and this drive shaft is not only operatively connected to the fan of the blower, but is also connected to a suitable brush rotatably mounted in the mouth of the nozzle.

As a result of the above general construction, the housing of the cleaner is usually of substantial height and this is objectionable in floor cleaners because it interferes with cleaning the surface beneath articles of furniture that may be distributed over the floor surface.

With the above in view, the present invention contemplates improving floor cleaners of the general type previously set forth by reducing the overall height of the cleaner to a minimum. According to this invention, the overall height of the cleaner is appreciably reduced without interfering with the effective operation of the cleaner by providing a construction wherein the blower fan revolves in a substantially horizontal plane and is of such construction as to occupy a space of relatively small height.

Another object of the present invention resides in the provision of a floor cleaner having an electric motor equipped with a ring type armature revolvable in a horizontal plane about a vertical axis and having means associated therewith for drawing air from the nozzle through the armature to the dust receptacle.

A further advantageous feature of the present invention resides in the provision of a vacuum cleaner of the type set forth above having means operatively connecting the armature of the motor to the brush in the nozzle of the vacuum cleaner for rotating the brush. This feature, as well as the foregoing and other objects, will be made more apparent as this description proceeds, especially when considered in connection with the accompanying drawings, wherein—

Figure 1 is a plan view of a floor cleaner hav-

ing the casing removed for the sake of clearness;

Figure 2 is a sectional view taken substantially on the plane indicated by the line 2—2 of Figure 1;

5 Figure 3 is a plan view of a floor cleaner having the top of the casing broken away for the sake of clearness and illustrating a slightly modified form of the invention;

Figure 4 is a sectional view taken substantially 10 on the plane indicated by the line 4—4 of Figure 3.

Referring to the embodiment of the invention illustrated in Figures 1 and 2, it will be noted that the reference character 10 designates a vacuum cleaner housing suitably supported on wheels 11 in a manner to permit the same to be propelled over the surface to be cleaned by a handle 12 suitably pivotally connected to the housing 10. The housing 10 is preferably formed of sheet metal and is provided with a downwardly opening nozzle 13 at the forward end. In accordance with conventional practice, a revoluble brush 14 is located in the nozzle and the opposite ends of the brush are supported in bearings 15 secured to the adjacent side walls of the housing. The 15 location of the brush 14 in the nozzle 13 is such that the bristles on the brush engage the surface to be cleaned and assist in effectively cleaning the latter.

The brush 14 is rotated by an electric motor 30 15 comprising a stator 16 and a rotor or armature 17. The armature 17 comprises a sheet metal annulus 18 and a hub 19 extending axially of the annulus and having a lining 20 of bearing material. The hub 19 is rotatably mounted on a spindle 21 having its axis extending vertically and having the lower end secured to a sheet metal plate 22 forming the bottom wall of the housing 10.

It follows from the above that the armature 40 17 is mounted in the housing 10 for rotation about a vertical axis in a substantially horizontal plane. In the present instance, the armature windings 23 are supported on the periphery of the annulus 18 and extend generally circumferentially of the annulus 18. As a result, the axial length of the armature 17 may be considerably reduced and this is desirable in that it renders it possible to correspondingly reduce the height of the housing 10.

The stator 16 has a coil 25 supported in the rear portion of the casing to one side of the armature 17 and has a core extending through the coil. The core is shown in Figure 1 as having pole pieces in the form of arms 26 extending from opposite ends of the coil around oppo-

site sides of the armature 17. The inner surfaces 21 of the arms 28 are formed concentric with the outer surface of the revoluble armature and are positioned in close proximity to the periphery of the armature in order to insure the necessary passage of flux between the permanent magnet and armature. It will also be observed from Figure 1 that the length of the arms 28 is such that these arms practically encircle the armature and this is also desirable in order to secure the proper electromagnetic action.

The electric motor, selected herein for the purpose of illustration, is preferably of the alternating current single phase type having a commutator 28 in the form of a ring secured to the inner surface of the annulus 18. As shown in Figure 2, the individual segments of the commutator ring 28 are secured to the inner surface of the annulus 18 by means of a ring type clip 29 and are insulated from the clip 29 by means of the ring of insulating material 30. The segments of the commutator ring 28 are respectively electrically connected to the various windings on the armature in accordance with the usual practice of winding single phase alternating current motors and are successively engaged by brushes in the form of a pair of rollers 31. The rollers 31 are revolvably mounted on studs 32 secured to and insulated from a supporting plate 33. The plate 33 extends horizontally over the top of the armature of the electric motor and is provided with upwardly extending marginal flanges 34 secured to the top wall of the housing 10. The forward end 35 of the plate 33 is bent downwardly beyond the armature ring 17 and forms the rear wall of the nozzle 13.

The hub 19 of the revoluble armature 17 is connected to the annulus 18 by means of a blower fan 36 having a bottom wall 37 extending parallel to the base plate 22 of the housing and formed with a centrally disposed hub 38 projecting upwardly into the annulus 18 through the lower side of the latter. As shown in Figure 2, the hub 38 telescopes the hub 19 of the armature and is permanently secured thereto for rotation as a unit therewith. The blower fan 36 is also provided with a top wall 41 extending parallel to the bottom wall 37 and having a centrally disposed hub 42. The hub 42 also extends into the annulus 18 through the bottom side of the latter and is concentrically arranged with respect to the hub 38. The two walls of the blower are secured together in spaced relationship by means of a plurality of fan blades 40 extending generally radially outwardly from the hub 38 and dividing the space between the walls into a series of air passages. Upon further reference to Figure 2, it will be noted that the top wall 41, in addition to being secured to the hub 19 of the armature by the blades 40, is also attached to a marginal flange 43 extending radially inwardly from the bottom edge of the annulus 18.

The upper ends of the hubs 38 and 42 project beyond the upper ends of the blades 40 to form an intake opening 44 for the blower. The intake opening 44 registers with an opening 45 in the plate 33 to establish communication between the space 46 confined by the plate 33 and the intake side of the blower 36. The forward end of the space 46 communicates with the interior of the nozzle 13 and, consequently, the air supplied to the intake side of the blower is drawn upwardly through the nozzle, as indicated by the arrows in Figure 2.

The air drawn into the blower 36 through the

central opening 44 flows downwardly through the armature of the motor and is discharged radially outwardly by the blades 40 into a space 47 surrounding the periphery of the blower fan. As shown in Figure 1, the space 47 gradually increases in cross sectional area from the point 48 to the discharge or outlet opening 49. The outlet opening 49 is in the form of a passage and communicates directly with the dust or dirt receptacle 50 of the vacuum cleaner. The receptacle 50 may be of conventional construction and is preferably suspended from the handle 12 of the vacuum cleaner in accordance with the usual practice.

From the foregoing, it will be noted that a substantial portion of the blower is located within the ring type armature 17 of the electric motor and is rotated as a unit with the armature in a substantially horizontal plane. It is also pointed out above that the armature windings extend generally circumferentially of the armature and that the commutator ring 28 is housed within the confines of the armature. It follows, therefore, that the dimension of the unit vertically of the housing is relatively small and this is especially advantageous in portable vacuum cleaners because it permits reducing the overall height of the housing to a minimum.

It has previously been stated that the brush 14 is revoluble in order to assist in cleaning the surface of the floor. In the present instance, a pulley 51 is secured to the upper end of the hub 19 for rotation therewith as a unit and this pulley is operatively connected to a pulley 52 on the brush by means of a flexible belt 53. The flexible belt 53 extends through the space 46 provided in the housing 10 above the plate 33 and is supported adjacent the brush by means of an idler pulley 54. The idler pulley 54 operates in a suitable depressed portion formed in the forward end of the plate 33 and the opposite ends of the pulley shaft are journaled in bearings carried by the opposite side walls of the depressed portion. Attention is called to the fact at this time that the pulley 51 is accessible through an opening 55 in the top wall of the housing 10. This opening is normally closed by a disc type closure 56 and may also suffice for connecting the various attachments in operative relationship to the blower.

Referring now to the embodiment of the invention illustrated in Figures 3 and 4, it will be noted that the principal difference between this embodiment and the one previously described is that the housing 60 of the vacuum cleaner is formed of cast metal sections. As shown particularly in Figure 4, the housing 60 is cast in two sections, a top section 61 and a bottom section 62. The bottom section 62 forms the support for the ring type armature and blower, which are also preferably formed of cast metal. The two sections are secured together by means of the fastener elements 63 and the space 47 extending around the periphery of the blower fan is formed by the bottom section 62.

It will also be noted that in the embodiment of the invention shown in Figures 3 and 4, the position of the stator 18' of the motor is reversed from the position shown in the first described form of this invention. In other words, the coil 25' is positioned in the forward end of the casing adjacent the revoluble brush 14' and the pole pieces 26' extend rearwardly from opposite ends of the coil. In other respects, the general arrangement and operation of the parts is the same as described in connection with the embodiment of the invention shown in Figures 1 and 2.

What I claim as my invention is:

1. In a vacuum cleaner, a substantially flat housing having a downwardly opening nozzle and a discharge opening spaced horizontally from and arranged at substantially the same elevation as said nozzle, an electric motor having an armature in the form of a ring mounted in the housing for rotation about a substantially vertical axis, an air passageway between said nozzle and one end of said ring, an air passageway between the other end of said ring and said discharge opening and means revoluble with the armature for circulating air through said passageways and axially through the armature from the nozzle to the discharge opening in the housing.

2. In a vacuum cleaner, a substantially flat housing having a downwardly opening nozzle and having a discharge opening, an electric motor having an armature in the form of a ring supported in the housing for rotation in a substantially horizontal plane, means in the housing establishing communication between the nozzle and one side of the ring, fan blades having portions extending axially through the ring from the side aforesaid thereof to draw air into the ring from the nozzle and having portions projecting generally radially outwardly from the axis of rotation of the ring, and means forming a space around the outer ends of the blades for receiving the air discharged by the blades and communicating with the discharge opening in said housing.

3. In a vacuum cleaner, a substantially flat housing having a downwardly opening nozzle and having a discharge opening, an electric motor having an armature in the form of a ring provided with a hub supported in the housing for rotation about a vertical axis, armature windings secured to the periphery of the ring and extending generally circumferentially of the ring, means in said housing providing a passage for air from the nozzle to one side of the ring, fan blades having portions secured to the hub and extending axially of the ring from the side aforesaid to the opposite side to draw air through the passage from the nozzle, said blades also having portions extending generally radially outwardly from the hub to discharge the air out of the opposite side of the ring, and means forming a space around the outer ends of the blades for receiving the air discharged by the blades and communicating with the discharged opening in said housing.

4. In a vacuum cleaner, a substantially flat housing having a downwardly opening nozzle and having a discharge opening, an electric motor having an armature in the form of a ring provided with a hub supported in the housing for rotation about a vertical axis, a fan comprising an annular outer wall extending into the ring

5 from one side thereof and having an annular portion concentric with the hub, an inner annular wall for the fan having a portion extending into the ring from the side aforesaid of the ring and having a hub telescopically receiving the hub of the ring and secured thereto, blades connecting said walls and arranged to draw air axially through the ring from the side thereof opposite the side aforesaid, means establishing communication between the nozzle and second named side, and means collecting the air discharged by the fan and conducting this air to the outlet opening in the housing.
